UNITED STATES PATENT OFFICE.

JAMES T. COWLEY, OF MINOT, MASSACHUSETTS, ASSIGNOR TO THE LAMSON COMPANY, OF NEWARK, NEW JERSEY, A CORPORATION OF NEW JERSEY.

PNEUMATIC AMMUNITION-CONVEYING APPARATUS.

1,148,080.

Specification of Letters Patent. Patented July 27, 1915.

Application filed October 11, 1909. Serial No. 522,100.

To all whom it may concern:

Be it known that I, JAMES T. COWLEY, of Minot, in the county of Plymouth and State of Massachusetts, have invented certain new and useful Improvements in Pneumatic Ammunition-Conveying Apparatus, of which the following is a specification.

This invention relates to improvements in pneumatic ammunition conveying apparatus, and its object is to provide a device for rapidly handling and safeguarding the conveyance of ammunition from the handling room of a magazine to a receiving station or turret adjacent the guns.

The present invention has been made and will be illustrated and described in connection with the pneumatic ammunition conveying apparatus of my prior application, Serial No. 451,061, filed August 31, 1908, and the invention consists of certain improvements by which a high speed and greater certainty and safety of action may be secured in that apparatus, but these improvements may be applied also to pneumatic ammunition conveying apparatus other than that shown in said prior application.

The invention relates particularly to the provision of means for removing from the conveyer the pushers used in conveying the ammunition and the construction of the pusher itself, the closing of the conveyer behind the receiving terminal when the receiving terminal is open, the control of the opening of the despatching terminal from the receiving terminal, the construction of the air admission mechanism, the construction of the powder receiver, and to means for cushioning and preventing recoil of the shell on its delivery in the receiving terminal, but includes other detail improvements, all as fully described hereafter and particularly pointed out in the claims.

In the accompanying drawings which illustrate a construction embodying my invention, Figure 1 is a diagrammatic view of the lower end of the system located in the handling room showing the despatching terminal and the air supply reservoir connected therewith. Fig. 2 is a continuation of the device shown in Fig. 1 showing the conveyer tube extending from the well to the turret with the receiving terminal at the upper end thereof and adjacent the guns. Fig. 3 is an enlarged elevation partly in section show-

ing the valve-operating mechanism located 55 on the opposite side of the despatching inlet shown in Fig. 1 with parts in position for the operator to admit air pressure to despatch the charge resting within the terminal. Fig. 4 is an enlarged elevation of the 60 despatching inlet showing the mechanism partly in section located in the front of the despatching terminal shown in Fig. 1 and showing the same in position for holding the gate locked while the load is in transit. Fig. 65 5 is a vertical longitudinal section through Fig. 3. Fig. 6 is a front elevation of Fig. 3 showing the mouth of the despatching inlet with the controlling gate and cap removed. Fig. 7 is an elevation of the inner face of 70 the gate at the despatching terminal. Fig. 8 is a detail of the valve-locking mechanism at the despatching terminal. Fig. 9 is a sectional view of the locking mechanism for controlling the gate, the operating lever and 75 the main air admission valve. Fig. 10 is an enlarged side elevation of the receiving terminal shown in Fig. 2 partly in section. Fig. 11 is a front elevation of Fig. 10 showing the powder receptacle and locking 80 mechanism in section and in normal position. Fig. 12 is an enlarged sectional view of the upper portion of the receptacle-locking and powder cushioning mechanism. Fig. 13 is a section on line 13—13 Fig. 10. Fig. 14 85 is a rear end elevation of Fig. 10 with a portion of the apron counter-balancing mechanism in section. Fig. 15 is a vertical sectional view on line 15—15 Fig. 10 looking in the direction of the arrow. Fig. 16 is an enlarged 90 sectional view on line 16—16 Fig. 10 looking in the direction of the arrow and showing in addition the shell-cushioning levers and a portion of the recoil mechanism. Fig. 17 is an enlarged side elevation of the shell- 95 cushioning lever and recoil mechanism shown in Figs. 10 and 16. Fig. 18 is a sectional view taken on line 18—18 Fig. 17 looking in the direction of the arrow. Fig. 19 is a rear elevation of the powder receptacle. Fig. 20 100 is a sectional view of the powder receptacle taken on line 20—20 Fig. 19. Fig. 21 is a sectional view showing the receptacle-locking mechanism in its normal position. Fig. 22 is an enlarged side elevation of the valve- 105 controlled connection between the upper bend of the conveyer tube and the return tube, showing parts in normal position.

Fig. 23 is a similar view to Fig. 22 showing the valve mechanism in section. Fig. 24 is a sectional view taken on line 24—24 Fig. 23. Fig. 25 is a detail sectional view of the cushioning spring shown in Fig. 10 and hereafter described. Fig. 26 is a front elevation of the pusher or carrier. Fig. 27 is a central sectional view on line 27—27 Fig. 26. Fig. 28 is a diagrammatic elevation on the same scale as Fig. 10, showing a modified arrangement of the devices for pneumatically controlling the gate and air admission mechanism from the turret.

Like letters of reference refer to like parts throughout the several views.

Referring to Figs. 1 and 2: A represents the handling room of a warship adjacent the magazine and from which the ammunition is required to be conveyed to the turret B for use in the guns.

1 represents a despatching terminal secured to the terminal base plate 2 in said handling room, and 3 is a conveyer tube connecting the terminal 1 with the receiving terminal 4 located in the turret B, said tube extending through the well 5 connecting the turret with the handling room. Through this tube 3, the ammunition is conveyed from the handling room to the turret by means of compressed air which acts upon a carrier or pusher 6 which is adapted to fit over the conical end of the shell and snugly within the tube 3, the powder bags preferably preceding the shell in transmission.

7 is a valve casing interposed in the upper bend in tube 3 adjacent the receiving terminal 4, and 8 is a return tube connected at its upper end with said casing 7 and extending downward through well 5, its lower end terminating at a point adjacent the despatching terminal 1. Through this tube the carriers or pushers which carry the ammunition to the receiving terminal are returned to the despatching terminal.

Compressed air for driving the charge is stored in a reservoir 9 which is connected by a supply pipe 10 with the despatching terminal 1. The compressed air reservoir 9 is connected (Fig. 1) with a source of air pressure by a pipe 9^a in which is located a reducing valve 9^b. The reservoir 9 contains sufficient air for the delivery of a charge but is of such size as to secure such a drop in pressure during transmission as to lower the speed of the ammunition at delivery and avoid shock. When the pressure in reservoir 9 has dropped below a determined point, air is admitted through the reducing valve 9^b and pipe 9^a until the pressure in said reservoir reaches normal, when the supply through pipe 9^a is automatically cut off.

The operation in brief is as follows: The delivery of a charge in the receiving terminal 4 acts to exhaust the air pressure in pipe 11 connecting the receiving terminal 4 with the

despatching terminal 1, which releases the gate 12 (Fig. 4) closing the entrance to the despatching terminal 1, allowing said gate 12 to be opened automatically by spring 13 located in cap 14 (Fig. 5), which cap is secured to the face of the terminal and in which the gate 12 is movably mounted. This exhaust of the air pressure in pipe 11 also closes the air admission valve 39 and cuts off the air from the conveyer, and locks the operating lever 47 to prevent the air being admitted until the receiving terminal is ready to receive another charge.

A charge consisting of two powder bags and shell with a pusher or carrier 6 on the conical end of the shell (Fig. 1) having been previously placed on the chute 15 as shown, is immediately pushed into the despatching terminal and the gate 12 closed, the charge remaining in the terminal until the charge previously despatched has been removed from the receiving terminal 4 in the turret and said terminal closed again to a position ready to receive another charge. As soon as the charge has been removed from the receiving terminal 4 and said terminal completely closed, the air pressure will build up in pipe 11 unlocking the operating lever 47 which when moved will admit air from the supply pipe 10 into the despatching terminal and transmit the charge resting in the terminal. When this charge arrives in the receiving terminal 4, the powder bags will pass through the upper bend in the conveyer tube 3 and into the hopper or receptacle 16. The arrival of the shell exhausts the air pressure in pipe 11 and also unlocks the receptacle 16 permitting it to be moved either to the right or left, for removing the powder bags, while either movement unlocks the apron 17 on its respective side, upon which the shell rolls out onto said apron into alignment with the gun. When this receptacle is moved through suitable link connections, a valve 20 located in casing 7 is rotated; this valve 20 is so constructed as to permit the passage of the powder and shell therethrough but is adapted to stop and hold the pusher or carrier 6 which drives the charge. When the valve 20 is turned, due to the link connections with the receptacle 16 and the movement of the same, this valve is brought into alignment with the return tube 8 allowing the pusher to drop down through said tube into the handling room A where it is received in pocket 18. On account of the interlocking mechanism located in the receiving terminal 4, it is necessary to close the apron 17 before closing the receptacle 16, and also on account of the connection between this receptacle 16 and valve 20, the conveying tube 3 is shut off from communication with the handling room at all times when the terminal 4 is open. The arrival of a charge in the receiving terminal 4 instantly

opens the gate 12, as heretofore described, by exhausting the pressure in pipe 11, permitting a new charge, which meanwhile has been placed on chute 15, to be moved into the 5 despatching terminal 1 and the gate closed, this operation being performed during the interval in which the charge is being removed from the receiving terminal and the receiving terminal is cut off from communication with the conveyer tube 3 by valve 20, while the act of closing the receiving terminal 4 instantly releases the controlling mechanism at the despatching terminal 1 permitting the operator to despatch a charge 10 resting in said terminal, and valve 20 opens communication between tube 3 and the receiving terminal. Through the action of another safety locking device located in the receiving terminal 4, it is impossible to close 15 said terminal to permit the despatch of another charge until the entire charge in said terminal 4 has been removed.

Turning now to the construction and operation of the apparatus in more detail: The 20 chute 15 (Fig. 1) is supported by and secured to the terminal base 2 at one end and at the other end by a standard 21. Suitably positioned in this chute 15 is the plunger 22 normally held by a spring 23 projecting a 25 suitable distance into said chute and adapted to prevent the shell from sliding forward until released by means of the treadle 24 connected with the plunger 22 by rod 25. When rapid handling of the charge is required, this plunger 22 may be held out of 30 position by any suitable clamp which may be released when desired.

When the gate 12 is closed by the operator pushing down on handle 26, the latches 27 engage with lugs 29 on gate 12 (see Figs. 3 and 4). Mounted on the lower end of one of the latches 27 is a dog 30 having a hook 31 on one end adapted to engage with a hook 32 of plunger 33. This dog 30 is provided 40 with an arm adapted to engage with one end of a stop screw 34 which is held in adjustment by check nut 35, for releasing the hook 31 from plunger 33 when said dog has been pulled back a predetermined amount by the 45 action of said plunger. A spring 36 acts to operate both the dog 30 and the latches 27. On gate 12 is a spring catch 311 (Figs. 6, 7) which engages one of the latches 27 to hold the latches out of position to engage stops 29 50 until the gate 12 is closed again. The catch 311 is thrown out of the way of latch 27 by cam 312 on the latch as the gate is closed. The operation of this gate locking mechanism is as follows:—When the air pressure 55 is maintained in the pipe 11, the plunger 33 is pushed forward until the hook 32 engages with the hook 31 on dog 30. As soon as the pressure is exhausted from the pipe 11, a spring 37 attached to the rear of plunger 33 60 will act to move said plunger to the left car-

rying with it the dog 30 and latches 27, releasing the lugs 29 secured to gate 12 and permitting said gate to be raised by means of spring 13 mounted within cap 14 and tube 14^a. As the latches 27 are moved out, spring 70 catch 311 is released by cam 312 and springs in behind the latch so as to hold it out, thus avoiding the latches returning to position to engage lugs 29 in case the opening of the gate is retarded by the pressure in the conveyer or otherwise. The air supply leading to pipe 11 is admitted through needle valve 38 which is adjusted to fill the pipe within a predetermined time owing to the supply being admitted through the restricted opening 75 at said needle valve 38. The arrival of the charge at the receiving terminal 4 opens the opposite end of this pipe 11 by means hereafter described permitting the air to immediately exhaust so that while there is a continuous supply through the needle valve 38, the pressure is not allowed to build up in said pipe until the opposite end of said pipe is closed, when the pressure builds up again and the cycle of operation is repeated. 80 When the gate is thus opened, the charge is moved into the conveyer tube 3 and the gate 12 closed by hand. On the closing of the gate latch 311 moves down over the incline of cam 312 and is thus thrown out into the 85 position shown in Fig. 6, in which it is held until the latches are again moved out to release lugs 29.

The admission of the compressed air from the air supply pipe 10 to the despatching terminal 1 is controlled by a valve 39 which is free to reciprocate within cylinder 40 in the upper part of the terminal casing or despatching inlet 1, and is normally held in position shown by means of spring 41 acting 90 against one end of said valve 39 (Fig. 5). In this position, the air is completely shut off from the conveyer tube 3. An auxiliary valve 44 is attached to the side of the terminal body or casing 1 and has a plunger 45 95 mounted therein and an air supply pipe 46 communicating with said air valve 44. To the outer end of the plunger 45 is attached the starting handle 47 which is pivoted at its lower end at 48 to the terminal casing 1; this handle is adapted to be moved by the operator when released by the locking mechanism heretofore described controlled by the removal of the charge and closing of the receiving terminal 4 in the turret B. When 100 the handle 47 is moved to the left, it acts through slot 49 and pin 50 to move the plunger 45 against the tension of spring 51 admitting air from pipe 46 through this auxiliary valve 44 and through a port 52 105 into the rear of the main valve cylinder 40 causing the valve 39 to be moved quickly to the right against the pressure of spring 41 admitting the air pressure in full volume 110 115 instantly from the supply pipe 10 through 120 125 130

ports 53 and 54 into the despatching terminal 1 and conveyer tube 3 in the rear of the charge to be despatched.

Mounted in the terminal casing 1 directly beneath the main air valve 39 is a rock shaft 55 upon which is secured a yoke 56 having a pin 56^a mounted thereon engaging a slot 57 in the main valve 39. On the outer end of this shaft 55 is keyed a crank 58 to which is 10 pivotally connected one end of the link 59, the opposite end of said link being pivoted to a bolt 60 adapted to slide in the frame of the terminal casing 1, the purpose of said bolt being to lock the gate 12 in its closed 15 position at all times when the main air valve 39 is open, and also to prevent the operating of said main valve 39 when the gate 12 is open. The end of bolt 60 registers with a hole 61 in gate 12 when said gate is in its 20 closed position (Fig. 3).

Attached to the side of the terminal casing 1 is a valve casing 62 connected on its upper side with the pipe 11 and in which valve casing 62 is mounted a plunger 63 (Figs. 8 and 9) held forward by means of a spring 64 acting in the rear of said plunger. When the air pressure in the pipe 11 is exhausted, the spring 64 forces this plunger 63 forward permitting the bolt 65 to be 30 thrown forward in front of the operating lever 47 by action of spring 67 mounted on the rear of collar 66 secured to said pin 65. When the air pressure is restored in pipe 11 due to the removal of the charge and the 35 closure of the receiving terminal 4, this pin 65 is withdrawn by action of plunger 63 engaging collar 66 secured to pin 65 and permitting the operating of the handle or lever 47 for despatching the charge.

40 Mechanism for locking the main air valve 39 open until the charge has arrived in receiving terminal 4, thus assuring the full delivery of the charge, is shown in Fig. 8, and consists of the bell crank lever 68 pivoted at 45 69 to one end of the plunger 45, the lower arm of said bell crank lever 68 carrying the lug 70 adapted to engage with a shoulder 71 on an arm 72 forming part of the crank 58 keyed to the rockshaft 55. A spring 73 mounted over the pivot 69 acts to hold the upper arm 74 of bell crank lever 68 in contact with the lower side of flange 71^a projecting laterally from arm 72 (see Fig. 3). The pin 75 rigidly secured to plunger 63 is 55 slidable within the recess or hole 76 and moves in unison with said plunger; the end of pin 75 is beveled at 77 and this beveled end co-operates with the upper arm 74 of bell crank lever 68. When the operator 60 throws lever 47 to the left (Fig. 3) to despatch a charge, valve 44 is opened and the main valve 39 shifted to the right in Fig. 5 to its open position and this movement of the main valve 39 acts through yoke 56 and 65 rockshaft 55 to swing arm 72 to the right in

Fig. 3 so as to carry shoulder 71 into engagement with the lug 70 as shown in Fig. 8, the spring 73 lifting arm 68 so as to bring lug 70 into locking engagement with shoulder 71 as soon as the latter passes to the right 70 of said lug; at the same time, the crank 58 acts through the link 59 to push bolt 60 into locking engagement with hole 61 in gate 12. The main valve 39 is thus held locked in its open position and gate 12 locked in its 75 closed position. When the lever 47 is swung to the left as above described, the upper end of the arm 74 of bell crank 68 is brought into a position directly in front of the beveled face 77 of pin 75 as shown in Fig. 8. 80

When plunger 63 is released due to the exhausting of air in pipe 11 caused by the arrival of the charge in terminal 4, the pin 75 is moved with said plunger 63 to the left (Fig. 9) by spring 64 causing the beveled face 77 to thrust the arm 74 to the right (see Fig. 8) thereby disengaging the lug 70 from the shoulder 71 permitting the main valve 39 to be closed by action of spring 41 and shutting off the supply of air to the despatching terminal 1. Upon the arrival of the charge at the receiving terminal 4, the powder bags followed by the shell, the pusher or carrier 6 covering the point of the shell and filling the tube and against which 90 the air pressure acts to drive the charge, said powder bags will ride up over the fingers 81 and the buffer roll 82 on the upper end of the recoil lever 83, said powder bags falling into the receptacle 16 (Fig. 10). The discharge 100 of the powder bags into this receptacle is cushioned by the action of the spring supported plate or cup 86 located in the lower end of the receptacle 16 (see Fig. 11). The springs 87 located on each side of said receptacle and supporting plate 86 are sufficient to support one powder bag within reach of the operator, but are so adjusted that the second bag comprising the full charge of powder, will depress the plate 86 110 to the bottom of the receptacle, the object being to elevate the lower bag of powder to within easy reach of the operator after the upper bag has been removed. The cup 86 is connected by a bail 86^a with two slides 86^b 115 movably mounted upon guide tubes 86^c supported by the frame of receptacle 16. The upper end of each tube 86^c is slidably mounted within a block 86^d mounted on the rod 88 with buffer washers 86^e arranged above and below said block. Each rod 88 is provided with a head 88^a at its upper end and with a nut 88^b at its lower end between which latter and a shoulder on the frame of receptacle 16 is arranged a spring 88^c. When the powder bags enter the receptacle, slides 86^b are depressed thus allowing the springs 88^c to force the rods 88 downwardly until the stops 88^d on heads 88^a engage the casing of receptacle 16. This downward movement of the 120 125 130

rod 88 which is connected with dog 90 (Fig. 10) swings the latter against the under side of bracket 90^a fixed to the frame of receiving terminal 4. When the powder receptacle is 5 opened by swinging it in either direction, the dog 90 rides over and snaps behind one or the other of two locking lugs 90^b provided on the under side of bracket 90^a (see Fig. 13). When all the powder is removed from 10 receptacle 16, the springs 87 lift slides 86^b, block 86^a and rods 88 to their normal position, the upward movement of the rod 88 which is connected with the dog 90 disengaging the latter from its locking lug 90^b. 15 The arrival of the shell in terminal 4 depresses fingers 81, the end of said shell striking the buffer roll 82 which stops the shell and cushions the impact of said shell by action of plunger 92 mounted in dashpot 20 93 and connected through link 94 with recoil lever 83. The dashpot 93 is provided with an adjustable air vent 95 regulated by a valve 96 to regulate the escape of air from the dashpot when the shell impinges on 25 buffer roll 82. The depression of finger 81 which is pivoted at 97 within terminal casing 4 (Fig. 32) acts through link 98 and bell crank lever 99 to lift valve stem 100 to open valve 101 connected with the upper 30 35 end of supply pipe 11 allowing air to escape from said pipe 11 to unlock and open gate 12, close valve 39 and lock the operating lever 47 against movement. Attached to each finger 81 is a gear segment 102 engaging with gear teeth on one end of lever 103 pivoted at 104 to casing 4, the opposite ends of 40 said levers 103 coöperating with arms 103^a forming part of apron 17. It is desirable to provide means for preventing the recoil of the roll 82 and shell 45 when stopped by the air cushion of dash pot 93 and for this purpose a friction clutch is used which holds the recoil lever 83 and roll 82 at the limit of their movement by 50 the advancing shell. Pivoted to recoil lever 83 at 111 is a pair of links 112 slidably mounted in clutches 113, which are pivoted at 114 within terminal casing 4. Bearing upon the upper sides of these links 112 are 55 rolls 115 to which spring pressure is applied through plungers 116 and springs 117 mounted in upper part of clutch 113. Above these rolls 115 are steel plates 118 set at a proper angle to permit the rolls 115 to 60 grip and hold the links 112 after the forward movement of recoil lever 83 preventing any recoil of said lever 83 due to the expansion of the air in dash pot 93, the shell thus being gradually stopped and left 65 in proper position in the terminal. These rolls do not act to grip the links 112 during the forward movement of the recoil lever 83 when the shell impinges upon the buffer roll 82. The recoil lever 83 is normally held in 70 75 80 85 90 95 100 105 110 115 120 125 130 135

of spring 119, one end of which is secured by pin 120 to said lever 83 the other end being secured to the inside of terminal casing 4.

The finger 81 is normally held projecting 70 into the path of the charge in terminal 4 by means of a spring 121 mounted over rod 122 which is slidably mounted in a boss 123 in the lower part of the terminal casing 4, while the upper end of said rod 122 is pivoted at 125 to the lower portion of finger 81. Pivoted at 126 to each apron 17 is link 128 the lower end of which is pivotally connected to the upper end of a link 127 which in turn is pivotally connected at its lower 80 end to the head of pin 127^a. This pin 127^a connects the two members 129 and 131 of a toggle whereof the member 129 is pivoted at 130 to the casing of the terminal and the member 131 is pivoted at 130^a to one of a 85 pair of clutch releasing arms 132 fast on rockshaft 133.

The object of this device is to release the 90 links 112 attached to recoil lever 83 when either apron 17 is open to remove the shell and allow said links to resume their normal position through action of spring 119 upon lever 83. This is accomplished by the clutch releasing arms 132 being pulled forward against the friction rolls 115 which 95 hold links 112 and recoil lever 83 in forward position causing said rolls to be moved out of frictional contact with angle plates 118 and links 112 releasing said links and allowing the recoil lever 83 to assume its 100 normal position.

Each apron 17 is rigidly fastened to a shaft 191 journaled in bearings on frame of the receiving terminal 4 and carrying at one end a segment 192 to which is fastened at 105 193 the upper end of a chain 194. The lower end of this chain is fastened to a rod 195 carrying two flanges 196 and 197, the former sliding freely on the rod 195 and the latter being fixed to the lower end thereof. 110 Mounted upon the two shafts 191 is a hanger 199 and each chain 194 with its depending rod 195 is inclosed by a tube 200 which forms part of this hanger. Within each tube is arranged a spring 198 located 115 between the two collars 196 and 197 and a spring 201 arranged between the collar 196 and the upper end of the hanger 199.

When either apron 17 is swung downwardly into its open position, its chain 194 and rod 195 are lifted, thereby compressing the springs 198 and 201, and the downward pressure of these springs on the rod and chain acting through the segment 192 serves to very nearly counter balance the weight of 120 125 130 135 apron 17. The two aprons 17 are made with arms 202 coöperating with an apron locking lever 203 pivotally mounted at 204 upon the cylindrical shank of a yoke like bracket 205 (Fig. 10) which supports the bell crank 99. 130

Links 206 connect the lever 203 with lugs 207 projecting from the hub of the segment 161, so that when receptacle 16 is swung to one side or the other of its normal intermediate closed position the movement transmitted to segment 161 through shaft 160 acts through the links 206 to rock the lever 203 so as to carry one end or the other thereof out of engagement with its arm 202.

10 Normally the lever 203 is in engagement with both of the arms 202 and serves to lock both aprons 17 in their closed positions.

When the receptacle 16 is swung to one side, its movement acts through the connections just described to free the apron upon that side of the receiving terminal toward which the receptacle 16 is swung. The operator pulls the freed apron down into its open position and the shell or projectile rolls out upon it into the trough 17^a at the outer end of the apron. From this trough, the projectile is pushed into the breach of the gun, the powder is transferred from the receptacle 16 to the gun and then 25 the apron and receptacle are closed in the order named. The entrance of the shell or projectile into the receiving terminal depresses both of the fingers 81 and when one of the aprons 17 is opened, its arm 103^a (Fig. 17) engages the right hand end of the lever 103 and locks the finger 81 which cooperates therewith in its depressed position. The other finger 81 at the opposite side of the terminal from the opened apron, not 35 being locked in its depressed position, is forced upwardly by its spring 121 and acts to roll the projectile out upon the opened apron.

Attached to the inner side of the terminal 40 casing 4 beneath the dashpot 93 is a valve casing 135 in which is mounted a plunger 136 (Fig. 21); connected with the lower part of casing 135 is a branch pipe 137 connecting at its opposite end with pipe 11. 45 With the pressure built up in pipe 11 and pipe 137, the parts within the casing 135 are in the position shown. In this position, the air pressure acting through port 138 and chamber 139, is exerted on the right 50 hand side of plunger 136 and holds said plunger in the position shown against the pressure of spring 140, the beveled portion 141 at the outer end of said plunger engaging with the dog 142, the outer end of said dog in the position shown engaging with notch 143 in plate 144 secured to the rear side of receptacle 16 locking said receptacle closed.

When the pressure in supply pipe 11, 60 branch tube 137 and chamber 139 is exhausted, the spring 140 forces the plunger 136 to the right, throwing the beveled portion 141 out of contact with the dog 142 allowing the same to be raised out of engagement 65 with notch 143 against the pressure of

spring 145 by the operator pushing down on either of the handles 146 (Figs. 10 and 19) one of which is located on either side of said receptacle 16, which handles act through links 147 to lift the lever 148 pivoted to receptacle 16 thereby raising said dog 142 and permitting the opening of said receptacle. When the dog 142 is lifted and the receptacle 16 moved to the right or left, the plate 144 attached to said receptacle is moved under the outer end of said dog preventing the same from dropping into notch 143. When the dog 142 is lifted out of notch 143, it carries with it a valve 150 through the action of pin 151 working in a slot 152 in said valve 150 causing the chambered portion 153 to be brought into communication with passage 154 and port 155 thereby venting the air pressure in casing 135 and pipe 137, thus unlocking the gate 12, unlocking the main air valve 39 so that the latter is at once closed by spring 41, and locking the operating lever 47.

The plate 144 serves to hold the latch 142 in its elevated position with valve 150 (Fig. 21) in its open position until the receptacle 16 is returned to its normal closed position. When this happens, the spring 145 throws the latch 142 down into the notch 143 and this movement of the latch acts through pin 151 to close the valve 150. The closing of the apron moves the arm 103^a out of engagement with the lever 103, so that the finger 81 which had been locked depressed is freed and elevated by its spring 121 allowing a spring 209 bearing at its upper end against the bracket 205 and at its lower end against a collar fixed to the stem 100 of a valve in casing 101 to close said valve. When both valves 101 and 150 have 105 been closed through the closing of the apron and receptacle, the pressure in pipe 11 is allowed to build up as air is admitted to the lower end of the pipe 11 through needle valve 38, and unlock the operating lever 47. 110

In Fig. 28 there is shown an arrangement of the devices for controlling the gate 12 and operating lever 47 from the projectile and powder receivers, by which a more rapid operation can be secured, the delay incident to building up the pressure through the needle valve 38, after exhaust through pipe 11, being avoided. In this modified construction the pressure for the release of the operating lever 47 is not built up through the needle valve, but transmitted from the air supply through the valves at the receiving terminal on the positioning of these valves by the closing of the projectile and powder receivers so as to connect the air supply with the pipe 11.

As shown in Fig. 28, in which the parts corresponding to those of the construction above described have the same references, the pipe 11 acts as an exhaust pipe in the 125

same manner as above described, but performs also the function of transmitting air pressure for releasing the lever 47, the connection of pipe 11 at the despatching terminal being the same as in the previous construction except that the inlet through needle valve 38 is omitted. At the receiving terminal, the pipe 11 connects through valve chamber 135 and pipe 11^a with valve 5 chamber 101, with which connects pipe 302 from any suitable compressed air supply, this pipe 302 being shown as extending down to the despatching terminal so as to be connected to reservoir 9. The valve chambers 135, 101, correspond to the same chambers of the construction previously described, and the valves are operated by, and in turn operate the same parts in exactly the same manner and for the same purpose 10 as in the previous construction, the only difference being in the construction and operation of the valves and valve passages. In valve chamber 135 the parts are the same and operate as in the previous construction 15 except that the valve 150 has, in addition to chambered portion 153, another chambered portion 303, which is adapted to connect a valve chamber with vent 304 for exhausting the valve chamber and pipe 11, and valve 20 chamber 101 has a valve 304^a provided with a chambered portion 305 and a vent 306, the former adapted to open connection between pipe 302 and 11^a, and the latter to exhaust chamber 101 and pipe 11^a when pipe 302 25 is closed to the chamber.

The operation of the construction will be understood from a brief description. As shown in Fig. 28, the parts are in the position they occupy for the despatch of ammunition with pressure transmitted from the pipe 302 through the valve chambers and pipes 11^a, 11, to release the starting lever 47. When the valve 304^a is raised by the delivery of a shell, through stem 100 and the 30 connections previously described, pipe 302 is closed to chamber 101 and vent 306 opened, thus exhausting pipe 11 and chambers 135, 101 and piston 136 then being operated by spring 140 to make possible the release of the powder receiver by one of the 35 handles 146. The movement of dog 142 by handle 146 moves valve 150 so as to close the connection with pipe 11^a and open vent 304 from chamber 135. When either of the 40 receivers is open, therefore, its corresponding chamber 135 or 101 is vented to the atmosphere so as to exhaust pipe 11. When both the receivers are closed, however, valves 150 and 304 are returned to the position shown in Fig. 28, thus closing vents 45 304, 306 and opening pipe 302 to pipe 11 through the valve chambers and pipe 11^a. The shaft 160 journaled in the lower portion of the terminal 4 is connected with and 50 serves as an oscillating support for recep-

tacle 16; fixed to this shaft within the terminal casing 4 is a gear segment 161, the upper end of which meshes with a pinion 162 secured to one end of the shaft 163 journaled in the side of the terminal casing. 55 The opposite end of this shaft 163 carries keyed thereto a crank 164, the ratio of the gear segment 161 and pinion 162 being such that said crank 164 makes one half a revolution each time the receptacle 16 is moved either to the right or to the left, and the crank 164 is connected with the lever 165 keyed to the rock shaft 166 by a yielding spring link 168 and a universal joint 169. The lever 170 is keyed to shaft 166 60 and pivotally connected by means of link 171 (see Figs. 23—24) with crank 172 secured to shaft 173 of a rotating valve 20 mounted in valve casing 7. When the receptacle 16 and valve 20 are in the position shown in Figs. 10 and 23, the opening in valve 20 registers with the bore of the conveyer tube 3, but when the receptacle 16 is moved either to the right or to the left through the connections above described, the 65 valve 20 is automatically rotated to register with the return tube 8. This valve 20 is provided with stops 174 on each side of the tube and projecting therein a sufficient distance to engage with and stop the pusher or carrier 6, but having space enough between said stops 174 to permit the passage of the powder and the shell. When the pusher or carrier arrives at these stops 174 in valve 20, the ring 223 on the forward end of the 70 pusher 6 (Fig. 27) engages said stops and the pusher is brought to a rest. The pawl 175 engages the rear side of the ring 223 on said pusher 6 preventing it from dropping back until the pawl 175 is released, which 75 takes place when the valve 20 has been rotated into alignment with the return tube. Previous to the arrival of the pusher at stops 174 the latch 176 mounted on the shaft 177 (upon which shaft the pawl 175 is secured) engages with the stop 178 on the valve casing 7, but after said pusher 6 has been brought to a stop within valve 20, the pawl 175 is still held slightly depressed by the side of the pusher against the tension of 80 spring 179 thus holding the latch 176 above the stop 178 so that the valve 20 can be rotated. When this valve 20 is rotated and coming into alignment with the return tube 8, the latch 176 rides up the cam surface 85 180 depressing the pawl 175 out of line with the pusher and allowing the pusher to drop from valve 20 into the return tube 8. The return of the valve 20 before the pusher has dropped is prevented by pivoted spring 125 pressed catch 176^a (Fig. 22) mounted on the top of catch 176, which yields to pass stop 178^a on the inside of casing 7 as the valve is moved into registry with return tube 8 to drop the pusher, but springs in- 130

ward into position to engage stop 178^a and prevent return movement of the valve unless the catch 176 is moved outward so as to move catch 176^a out of line with stop 178^a, which occurs when the pusher has dropped past spring pressed pawl 175, the pawl 175 being then thrown inward by spring 179 to throw catch 176 outward as the catch 176 moves back off the cam 180. If the pusher 5 has not dropped so as to release pawl 175, this pawl is held depressed, thus holding catch 176^a in position to engage stop 178^a and prevent the return movement of the valve. If the pusher should not drop completely out of the valve after passing pawl 10 175, the return movement of the valve 20 will be prevented by the pusher, so that the valve 20 can never be returned until the pusher has dropped into the return tube 20 clear of the valve 20 and the return tube will then be closed at its upper end by the valve 20 as it returns to normal position to open conveyer tube 3 to the receiving terminal.

25 The return tube is preferably somewhat larger than the pusher, so as to permit the air to escape around the pusher, thus avoiding any opening for escape of air at the bottom of the tube. It is obvious that the 30 co-action between latch 176 and pawl 175 makes it impossible to rotate valve 20 out of alignment with tube 3 until the pusher 6 is in proper position within said valve and as above stated the valve cannot be returned 35 to open tube 3 to the receiving terminal until the pusher has been delivered from the valve. The yoke 211 forming part of the universal joint 169 (Fig. 25) is secured to the lower end of a rod 212 provided at its upper end 40 with a head 213. The rod 212 extends into a sleeve 214 containing a spring 215 arranged between the head 213 and the lower end of said casing. The upper end of the casing 214 is pivotally connected with the 45 arm 165. It will thus be clear that should the operator attempt by force to open the receptacle 16 while latch 176 is in engagement with shoulder 178, or in other words, when there is no pusher within the valve, then 50 the link 168 will yield, thus preventing injury to the mechanism connecting the receptacle 16 with the switch valve 20. The crank 164 is preferably arranged to start the valve slowly which aids in avoiding danger 55 of injury to the valve or connections. It is apparent that the means employed for stopping the pushers and removing them from the conveyer system, and for closing the conveyer behind the receiving terminal may be 60 used without the return tube, the pushers being simply dropped out of the tube into the turret or delivered at any point desired to be conveyed back to the receiving terminal as required and in any convenient manner.

It will be seen that the valve 20 closes the conveyer tube 3 and the return tube 8 behind the receiving terminal, when the receiving terminal is opened, and cannot be returned to position to open tube 3 behind the receiving terminal until the receiving terminal is closed. This avoids all danger of fire passing back through the conveyer tube or the return tube to the handling room from the turret, although the gate at the despatching 70 terminal is open, thus permitting the safe insertion of ammunition in the conveyer tube for despatch while ammunition is being removed from the conveyer in the turret, so that successive charges of ammunition may 80 be sent very rapidly with safety. The pusher, also, acts to close the conveyer tube 3 behind the receiving terminal during the opening of the powder receiver, being held positively in position to close the tube by 85 stops 174, 175, thus safeguarding the handling room from connection with the turret during the delivery of the ammunition into the receiving terminal, and providing another safeguard against the sending of another charge into the receiving terminal until the latter is ready to receive it. Moreover, ammunition cannot be despatched until the pusher is removed from the system as the valve 20 is locked against return and the 90 powder receiver cannot be closed until the pusher is dropped from the valve, so that the operating lever 47 is locked closed to prevent the admission of air to the conveyer tube.

In order to operate the valve 20 without 100 a carrier or pusher therein, it is necessary to raise the latch 176 by hand, for which purpose an opening in the valve casing may be provided and normally closed by a suitable door. The valve may be rotated by handle 217 (Fig. 2), the link 171 being detached from the valve. When the opening through the valve 20 is in alignment with the return tube 8, the upper end of this opening is in alignment with an opening 185 in the upper portion of valve casing 7. This opening 185 is normally closed by a cover 186 (See Fig. 22) adapted to rotate about pivot 187. Mounted in this cover is a cam actuated plunger 188, the lower end of which is close 110 to the periphery of valve 20. The arrangement of this plunger 188 is such that the cover 186 cannot be rotated except when the opening in valve 20 is in alignment with return tube 8. In this position, there is a 115 pocket 189 in valve 20 which allows the plunger 188 to be dropped therein, but the periphery of the valve 20 will prevent the plunger from being lowered in any other position, thereby preventing the opening of the cover 186. This opening 185 and the provision for tripping catch 176 by hand 120 are for returning the coverings of the powder bags through tube 8 to the handling room, or for access to the interior of the valve for any 125 130 135

purpose, and the object of the locking device is to prevent valve 20 from being rotated while cover 186 is open, or the opening of cover 186 except when the valve 20 is in position to close tube 3 to the valve, thereby preventing possible injury to the operator.

Pivoted to the pocket 18 (Fig. 1) at the lower end of the return tube 8, is a normally closed door 18^a locked by a latch 18^b which is adapted to be released by the operator grasping handle 18^c to permit the opening of the door and the removal of the pushers or powder bag coverings.

The terminal casing 4 with the receivers 15 and the valve casing 7 are normally closed so as to form a chamber that is normally isolated and sealed from the interior of the turret. During the transit of ammunition the air in advance of the ammunition is 20 forced out of the chamber into the turret past the outwardly opening spring pressed valves 313 controlling ports at the bottom of the casing 4, and valve 314 controlling a port in valve casing 7. This port and valve 314 25 in casing 7 is preferably used, as valve 314 will open to permit the escape of the air from the conveyer tube behind the pusher, when the pusher has reached the stops 174, the air passing from the tube to the casing 7 30 through opening 315 which is not closed by the rear end of the pusher when stopped by stops 174.

The pusher or piston 6 is shown in detail in Figs. 26 and 27, and comprises a cylindrical body 219 having a ring 220 riveted to its rear end and a ring 221 riveted to its front end together with a shoulder ring 222. Surrounding the ring 220 in front of the shoulder 222 is a buffer ring 223 fastened to ring 40 221 by screws 224, this ring 223 being of suitable composition and forming a cushioning stop for the pusher and a wearing ring for supporting the weight of the shell. The front ring 221 is made with a reentrant flange 225 provided with a narrow inner bearing for the shell, shown as formed of a plurality of shell-engaging lugs 226 integral with flange 225, ribs 227 being formed behind flange 225 for reinforcing said flange. 45 The body 219 is hollow to receive the end of the shell and leave it free for the shell to pivot on the bearing formed by lugs 226 in turning bends of the conveyer tube. The rear end of the pusher or piston is closed by 50 a plate 228 riveted to the ring 220, this plate 228 sustaining the conveying pressure. Lugs 231 are provided on the exterior of the rear ring 220 to engage the interior of the tube 3 and support the rear end of the pusher and shell therein. Fixed to the exterior of the body 219 near the rear end thereof, is a flexible piston ring, shown as formed of a skirt or ring 229 of leather or the like whose rear end is held distended by a plurality of 55 springs 230. The open end of the pusher is

applied to the nose of the shell as indicated by dotted lines with lugs 226 resting against said shell and when the pusher is shoved into the tube 3 with the charge and the air pressure admitted to said tube behind the pusher, 70 said pressure further distends the free portion of skirt 229 and forces it to fit snugly against the interior of the tube 3 so as to form a piston and prevent leakage of air past skirt 229.

The conveyer tube 3 comprises an upper section connected with and adapted to rotate with the receiving terminal 4, and a lower section connected with the despatching terminal 1, said upper and lower sections being 80 connected together by a swivel joint 209 so that the upper turret section can rotate relatively to the lower section. The carrier return tube 8 is likewise made up of an upper turret section and a lower section connected 85 by a connection 209 so that the delivery end 18 of the carrier return tube can be swung about to suit the convenience of the operator at the despatching terminal 1. In order also to provide for movement of the upper portion of pipe 11 with the turret relatively to the lower part of said pipe which is connected with the despatching terminal 1, said upper and lower portions or sections are connected by an intermediate flexible sec- 90 95 tion 210.

It is desirable to provide for returning ammunition through the tube 3, for practice in the use of the apparatus or other purposes, and this may readily be done by retarding the escape of air from the lower end of the conveyer tube so as to cushion the ammunition. The apparatus may also be operated by hand so as to send up the ammunition at the speed desired in practice, without 100 using the automatic control or safety devices. For this purpose, the air pipe 10 is provided with a gate valve 10^a, which may be opened and closed by hand for sending up or returning through the tube 3 pushers 105 with shells or full charges of ammunition thereon, the admission of air being controlled by the gate valve to secure the speed desired. For lowering the ammunition, gate valve 10^a may be opened to admit pressure 110 behind the pusher and ammunition in the receiving terminal and the ammunition then lowered at the desired speed by opening gate 12, or a special aperture at the despatching terminal provided for this purpose, to 115 permit the air to escape slowly. For this operation the shafts 27^a and 25 are turned by wrenches so as to release latches 27 and 28 which lock gate 12 closed and to open the main valve 39 independently of the auxiliary valve 45, the ends of these shafts being squared to permit them to be turned by a wrench from outside the conveyer. A check valve 10^b is preferably interposed in the air supply pipe 10 to prevent ammunition com- 120 125 130

ing down the tube rapidly in case it should descend by accident or otherwise while receiver 9 is not under pressure.

While the invention has been illustrated and described in connection with an apparatus for transmitting at one time the complete charge for a gun, that is, both powder and projectile, it will be understood that the features forming the invention may 5 be applied in apparatus designed for transmitting only the projectile or the powder, or for transmitting projectiles and powder separately, and that other modifications may 10 be made in the apparatus shown while retaining the invention defined by the claims. 15

What I claim is:—

1. In a pneumatic ammunition conveying apparatus, a despatching terminal, a receiving terminal, a conveyer connecting said 20 terminals, an air supply, an air valve, means for locking said air valve open during the transit of the ammunition, means for unlocking and closing said air valve, and means controlled from the receiving terminal 25 for preventing the opening of the air valve until the previously despatched ammunition has been removed from the receiving terminal.

2. In a pneumatic ammunition conveying apparatus, a despatching terminal, a receiving terminal, a conveyer connecting said terminals, an air supply, an air valve, means for locking said air valve open during the transit of the ammunition, means for unlocking and closing said air valve when the ammunition has reached the receiving terminal and means controlled from the receiving terminal for preventing the opening of said air valve until the previously 35 despatched ammunition has been removed from the receiving terminal.

3. In a pneumatic ammunition conveying apparatus, a despatching terminal, a receiving terminal, a conveyer connecting said terminals, an air supply, an air valve, means for locking said air valve open during the transit of the ammunition, means for unlocking and closing said air valve when the ammunition has arrived at the receiving terminal, means for opening said air valve and means for locking the valve opening means against operation until the receiving terminal is ready to receive ammunition.

4. In a pneumatic ammunition conveying apparatus, a despatching terminal, a receiving terminal comprising a receptacle adapted to be opened and closed, a conveyer connecting said terminals, an air supply, air admission mechanism, means for locking said air admission mechanism against movement to cut off the air while ammunition is in transit, means for operating the air admission mechanism to cut off the air when transit is completed, and means for prevent-

ing the operation of said air admission mechanism to admit air until the ammunition has been removed from the receptacle and the receptacle has been closed.

5. In a pneumatic ammunition conveying apparatus, a despatching terminal, a receiving terminal, a conveyer connecting said terminals, an air supply, a pressure operated main air valve, an auxiliary valve controlling the opening of said main valve, locking devices for locking said main valve open while the ammunition is in transit, and devices pneumatically controlled from the receiving terminal for automatically unlocking and closing said main valve when the ammunition has arrived at the receiving terminal and for preventing the opening of the main valve until the receiving terminal is ready to receive ammunition.

6. In a pneumatic ammunition conveying apparatus, a despatching terminal, a receiving terminal, a conveyer connecting said terminals, an air supply, an air valve, locking devices for locking said valve open while the ammunition is in transit, and pneumatically controlled devices for automatically unlocking and closing said air valve when the ammunition has arrived at the receiving terminal and for preventing the opening of the valve until the receiving terminal is ready to receive ammunition.

7. In a pneumatic ammunition conveying apparatus, a despatching terminal, a receiving terminal, a conveyer connecting said terminals, an air supply, a pressure operated main air valve, an auxiliary valve controlling the opening of the main valve, means for locking said main valve open while the ammunition is in transit, and means for controlling the auxiliary valve from the receiving terminal.

8. In a pneumatic ammunition conveying apparatus, a despatching terminal, a receiving terminal, a conveyer connecting said terminals, an air supply, a pressure operated main air valve, an auxiliary valve controlling the opening of the main valve, means for locking said main valve open while the ammunition is in transit, means for unlocking and closing said main valve when the ammunition has arrived at the receiving terminal and means for preventing the opening of said main valve until the previously despatched ammunition has been removed from the receiving terminal.

9. In a pneumatic ammunition conveying apparatus, a despatching terminal, a receiving terminal, a conveyer connecting said terminals, an air supply, a pressure operated main air valve, an auxiliary valve controlling the opening of said main valve, means for locking said main valve open while the ammunition is in transit, means for unlocking and closing said main valve

when the ammunition has arrived at the receiving terminal, and a locking device locking the auxiliary valve closed to prevent the opening of the main valve until the receiving terminal is ready to receive ammunition.

10. In a pneumatic ammunition conveying apparatus, a despatching terminal, a receiving terminal adapted to be opened and closed, a conveyer connecting said terminals, an air supply, a pressure operated main air valve, an auxiliary valve controlling the opening of said main valve, means for locking said main valve open while the ammunition is in transit, automatic means for unlocking and closing said main valve and a locking device for the auxiliary valve unlocked by the closing of the receiving terminal to permit the auxiliary valve to be operated to open the main valve.

11. In a pneumatic ammunition conveying apparatus, a despatching terminal, a receiving terminal, a conveyer connecting said terminals, an air supply, a pressure operated main air valve, an auxiliary valve controlling the opening of said main valve, automatic means for closing said main valve, a locking device for locking the auxiliary valve against movement to open the main valve, and means controlled from the receiving terminal for unlocking said auxiliary valve when the receiving terminal is ready to receive ammunition.

12. In a pneumatic ammunition conveying apparatus, a despatching terminal, a receiving terminal, a conveyer connecting said terminals, an air supply, a pressure operated main air valve, an auxiliary valve controlling the opening of said main valve, and controlling devices including means for automatically closing said main valve and locking said auxiliary valve against movement to open the main valve and for pneumatically unlocking said auxiliary valve from the receiving terminal to permit it to be operated to open the main valve.

13. In a pneumatic ammunition conveying apparatus, a despatching terminal, a receiving terminal, a conveyer connecting said terminals, an air supply, a pressure operated main air valve, an auxiliary valve controlling the opening of said main valve, and controlling devices including a combination of means for automatically closing said main valve and locking said auxiliary valve against movement to open the main valve and means for transmitting pneumatic pressure from the receiving terminal to the despatching terminal to control the locking and unlocking of the auxiliary valve.

14. In a pneumatic ammunition conveying apparatus, a despatching terminal, a receiving terminal, a conveyer connecting said terminals, an air supply, a main air valve,

an auxiliary valve controlling the opening of said main valve, means for closing the main valve and operating the auxiliary valve to open the main valve and means for controlling from the receiving terminal the closing of the main valve and operation of the auxiliary valve to open the main valve.

15. In a pneumatic ammunition conveying apparatus, a despatching terminal, a receiving terminal, a conveyer connecting said terminals, an air supply, a main air valve, an auxiliary valve controlling the opening of said main valve, means controlled by the transit of ammunition for closing the main valve, and means for controlling from the receiving terminal the operation of the auxiliary valve to open the main valve.

16. In a pneumatic ammunition conveying apparatus, a despatching terminal, a receiving terminal, a conveyer connecting said terminals, an air supply, locking devices for locking the despatching terminal closed, means controlled from the receiving terminal for unlocking said despatching terminal to permit ammunition to be introduced into the despatching terminal while ammunition is being removed from the receiving terminal and means for preventing the despatch of ammunition until the previously despatched ammunition has been removed from the receiving terminal.

17. In a pneumatic ammunition conveying apparatus, a despatching terminal, a receiving terminal, a conveyer connecting said terminals, an air supply, locking devices for locking the despatching terminal closed, means controlled from the receiving terminal for unlocking said despatching terminal to permit ammunition to be introduced into the despatching terminal while ammunition is being removed from the receiving terminal, and means for closing the conveyer between the despatching terminal and receiving terminal until the receiving terminal is ready to receive ammunition.

18. In a pneumatic ammunition conveying apparatus, a despatching terminal, a receiving terminal, a conveyer connecting said terminals, an air supply, a gate closing the despatching terminal, locking devices for locking said gate closed, means controlled by the transit of ammunition for unlocking said gate and means for preventing the despatch of ammunition until the previously despatched ammunition has been removed from the receiving terminal.

19. In a pneumatic ammunition conveying apparatus, a despatching terminal, a receiving terminal, a conveyer connecting said terminals, an air supply, a gate closing the despatching terminal, locking devices for locking said gate closed, means pneumatically controlled from the receiving terminal to unlock the gate when the ammunition has

arrived at the receiving terminal and means for preventing the despatch of ammunition until the previously despatched ammunition has been removed from the receiving terminal.

5 20. In a pneumatic ammunition conveying apparatus, a despatching terminal, a receiving terminal, a conveyer connecting said terminals, an air supply, means for locking the despatching terminal closed during the transit of ammunition and unlocking it by the delivery of the ammunition to the receiving terminal, and means controlled from the receiving terminal for preventing the despatch of ammunition until the previously despatched ammunition has been removed from the receiving terminal.

10 21. In a pneumatic ammunition conveying apparatus, a despatching terminal, a receiving terminal, a conveyer connecting said terminals, an air supply, means for locking the despatching terminal closed during the transit of ammunition and unlocking it by the delivery of the ammunition to the receiving terminal, means for opening and closing the receiving terminal and means for preventing the despatching of ammunition until the previously despatched ammunition has been removed from the receiving terminal and the receiving terminal has been closed.

15 22. In a pneumatic ammunition conveyer, a despatching terminal, a receiving terminal, a conveyer connecting said terminals, an air supply, a gate closing the despatching terminal, an air valve, locking devices for locking said gate closed while the air valve is open, means controlled by the transit of ammunition for automatically unlocking said gate and closing said valve and means for preventing the opening of the valve until the previously despatched ammunition has been removed from the receiving terminal.

20 23. In a pneumatic ammunition conveyer, a despatching terminal, a receiving terminal, a conveyer connecting said terminals, an air supply, means for closing the despatching terminal, an air valve, locking devices for locking said despatching terminal closed while the air valve is open, means controlled by the transit of ammunition for automatically unlocking said despatching terminal and closing said valve, and means controlled from the receiving terminal for preventing the opening of the air valve until the previously despatched ammunition has been removed from the receiving terminal.

25 24. In a pneumatic ammunition conveying apparatus, a despatching terminal, a receiving terminal, a conveyer connecting said terminals, an air supply, an air valve, means for closing the despatching terminal, locking devices for locking said despatching terminal closed and said air valve open while the ammunition is in transit, and pneumati-

cally controlled devices for unlocking said despatching terminal and closing the air valve when the ammunition has arrived at the receiving terminal and for preventing the opening of the air valve until the previously despatched ammunition has been removed from the receiving terminal.

70 25. In a pneumatic ammunition conveying apparatus, a despatching terminal, a receiving terminal, a conveyer connecting said terminals, an air supply, an air valve, a gate closing the despatching terminal, locking devices for locking said gate closed and said air valve open while the ammunition is in transit, and pneumatically controlled devices for unlocking said gate and closing said air valve when the ammunition has arrived at the receiving terminal and for preventing the opening of the air valve until the receiving terminal is ready to receive ammunition.

75 26. In a pneumatic ammunition conveying apparatus, a despatching terminal, a receiving terminal, a conveyer connecting said terminals, an air supply, an air valve, a gate closing the despatching terminal, locking devices for locking said gate closed while a charge is in transit, means for unlocking said gate when the ammunition has arrived at the receiving terminal, and locking devices controlled by the closing of the receiving terminal to prevent the opening of the air valve until the receiving terminal is fully closed.

80 27. In a pneumatic ammunition conveying apparatus, a despatching terminal, a receiving terminal, a conveyer connecting said terminals, an air supply, a main air valve, a manually operated auxiliary valve at the despatching terminal controlling the opening of said main valve, means for closing said despatching terminal, means for locking said despatching terminal closed while a charge is in transit and unlocking said despatching terminal when the ammunition has arrived at the receiving terminal, means for closing said main valve when the admission of air for transit of ammunition is completed, and means for locking the auxiliary valve to prevent the opening of the main valve until the receiving terminal is ready to receive ammunition.

85 28. In a pneumatic ammunition conveying apparatus, a despatching terminal, a receiving terminal, a conveyer connecting said terminals, a main air valve, an auxiliary valve controlling the opening of said main valve, locking devices for locking said auxiliary valve closed, means for closing the despatching terminal, locking devices for locking said despatching terminal closed during the transit of ammunition, and pneumatic means for unlocking said despatching terminal by the release of pressure at the receiving terminal and for un-

locking said auxiliary valve by the transmission of pressure from the receiving terminal to the despatching terminal.

29. In a pneumatic ammunition conveying apparatus, a conveyer system including a despatching terminal, a receiving terminal means for opening and closing the receiving terminal and a conveyer connecting said terminals, in combination with means for automatically closing the conveyer system between the receiving terminal and despatching terminal when the receiving terminal is opened.

30. In a pneumatic ammunition conveying apparatus, a conveyer system including a despatching terminal, a receiving terminal means for opening and closing the receiving terminal and a conveyer connecting said terminals, in combination with means for closing the conveyer system between the receiving terminal and despatching terminal when the receiving terminal is open and preventing the opening of communication between the receiving terminal and the despatching terminal until the receiving terminal is closed.

31. In a pneumatic ammunition conveying apparatus, a conveyer system including a despatching terminal, a receiving terminal means for opening and closing the receiving terminal and a conveyer connecting said terminals, in combination with means for locking the despatching terminal closed during the transit of ammunition and unlocking said despatching terminal when the ammunition has arrived at the receiving terminal, and means for closing the conveyer system between the receiving terminal and the despatching terminal when the receiving terminal is open and preventing the opening of communication between the receiving terminal and the despatching terminal until the receiving terminal is closed.

32. In a pneumatic ammunition conveying apparatus, a conveyer system including a despatching terminal, a receiving terminal means for opening and closing the receiving terminal and a conveyer connecting said terminals, in combination with a gate closing the despatching terminal, locking devices for locking said gate closed, means controlled by the transit of ammunition for unlocking said gate, and means for closing the conveyer system between the receiving terminal and the despatching terminal when the receiving terminal is open and preventing the opening of communication between the receiving terminal and the despatching terminal until the receiving terminal is closed.

33. In a pneumatic ammunition conveying apparatus, a conveyer system including a despatching terminal, a receiving terminal means for opening and closing the receiving terminal

and a conveyer connecting said terminals, in combination with means for closing the despatching terminal, locking devices for locking said despatching terminal closed, means controlled by the transit of ammunition for unlocking said despatching terminal, means for closing the conveyer system between the receiving terminal and the despatching terminal when the receiving terminal is open and preventing the opening of communication between the receiving terminal and the despatching terminal until the receiving terminal is closed, and means for controlling from the receiving terminal the despatch of ammunition.

34. In a pneumatic ammunition conveying apparatus, a conveyer system including a despatching terminal, a receiving terminal means for opening and closing the receiving terminal and a conveyer connecting said terminals, in combination with means for closing the despatching terminal, locking devices for locking said despatching terminal closed, means controlled by the transit of ammunition for unlocking said despatching terminal, means for closing the conveyer system between the receiving terminal and the despatching terminal, when the receiving terminal is open and preventing the opening of communication between the receiving terminal and the despatching terminal until the receiving terminal is closed, manually operated devices at the despatching station for despatching ammunition, and means for controlling said devices to prevent the despatch of ammunition until the receiving terminal is closed.

35. In a pneumatic ammunition conveying apparatus, a despatching terminal, a receiving terminal, a conveyer connecting said terminals, means for opening and closing the receiving terminal and means operated by the opening and closing of the receiving terminal to close and open the conveyer behind the receiving terminal when the receiving terminal is opened and closed.

36. In a pneumatic ammunition conveying apparatus, a despatching terminal, a receiving terminal, a conveyer connecting said terminals, a pusher closing the conveyer and moving with the ammunition, and devices at the receiving terminal for stopping the pusher and holding it in position to close the conveyer behind the receiving terminal, while allowing the ammunition to pass onward.

37. In a pneumatic ammunition conveying apparatus, a despatching terminal, a receiving terminal, a conveyer connecting said terminals, a pusher closing the conveyer and moving with the ammunition, devices at the receiving terminal for stopping the pusher and holding it in position to close the conveyer behind the receiving terminal, while allowing the ammunition to pass on-

ward, and means operated from the receiving terminal for releasing said pusher.

38. In a pneumatic ammunition conveying apparatus, a despatching terminal, a receiving terminal, a conveyer connecting said terminals, a pusher moving with the ammunition, devices at the receiving terminal for stopping the pusher while allowing the ammunition to pass onward, an opening 10 from the conveyer, and means for delivering the pusher from the conveyer through said opening.

39. In a pneumatic ammunition conveying apparatus, a despatching terminal, a receiving terminal, a conveyer connecting said terminals, a pusher moving with the ammunition, devices at the receiving terminal for stopping the pusher while allowing the ammunition to pass onward, an opening 15 from the conveyer, and a valve normally closing said opening and adapted when moved to deliver said pusher from the conveyer to said opening and close the conveyer behind the receiving terminal while 20 the valve is out of normal position.

40. In a pneumatic ammunition conveying apparatus, a despatching terminal, a receiving terminal, a conveyer connecting said terminals, a pusher closing the conveyer and 25 moving with the ammunition, devices at the receiving terminal for stopping the pusher and holding it in position to close the conveyer behind the receiving terminal while allowing the ammunition to pass onward, an opening 30 from the conveyer, a valve normally closing said opening and adapted when moved to deliver said pusher from the conveyer to said opening and close the conveyer behind the receiving terminal while 35 the valve is out of normal position, and means for locking said valve in normal position until the pusher has been received and 40 in pusher delivering position until the pusher has been delivered from the conveyer.

41. In a pneumatic ammunition conveying apparatus, a despatching terminal, a receiving terminal, a conveyer connecting said terminals, a pusher moving with the ammunition, devices at the receiving terminal for stopping the pusher while allowing the ammunition to pass onward, an opening 45 from the conveyer, a valve normally closing said opening and adapted when moved to deliver said pusher from the conveyer to said opening and close the conveyer behind the receiving terminal while the valve is out of normal position, and an automatic relief valve opening to permit the escape of air 50 behind the pusher when the pusher is stopped.

42. In a pneumatic ammunition conveying apparatus, a despatching terminal, a receiving terminal, a conveyer connecting said terminals, a pusher moving with the ammu-

tion, a pusher transferrer at the receiving terminal, devices for stopping the pusher in position for the action of said trans- 70 ferrer, means for moving said trans- ferrer to deliver the pusher from the conveyer, and a catch for holding said trans- ferrer in normal position released by the receipt of a pusher.

43. In a pneumatic ammunition conveying apparatus, a despatching terminal, a receiving terminal, a conveyer connecting said terminals, a pusher moving with the ammunition, a pusher trans- 75 ferrer at the receiving terminal, devices for stopping the pusher in position for the action of said trans- ferrer, means for moving said trans- ferrer to de- 80 liver the pusher from the conveyer, a catch for holding said trans- ferrer in normal po- 85 sition released by the receipt of a pusher, and a catch for preventing the return of the trans- ferrer released by the delivery of a pusher.

44. In a pneumatic ammunition conveying apparatus, a despatching terminal, a receiving terminal, a conveyer connecting said terminals, a pusher moving with the ammu- 90 nition, a pusher trans- 95 ferrer at the receiving terminal, devices for stopping the pusher in position for the action of said trans- ferrer, means operated by the opening and closing of the receiving terminal for moving said trans- ferrer to deliver the pusher from the conveyer and return the trans- ferrer to nor- 100 mal position, and means for locking the trans- ferrer against movement until the pusher is received and against return move- 105 ment until the pusher is delivered from the conveyer.

45. In a pneumatic ammunition conveying apparatus, a despatching terminal, a receiving terminal, a conveyer connecting said terminals, a pusher moving with the ammu- 110 nition, a stop at the receiving terminal acting to stop the pusher while allowing the ammu- 115 nition to pass onward, a catch for holding the pusher against backward movement, and means operated from the receiving terminal for releasing the catch.

46. In an apparatus of the class described, a conveyer, a pusher, means to unload said pusher, and a pusher conduit connecting with the conveyer for receiving the pusher after transit.

47. In an apparatus of the class described, a conveyer, a pusher, a pusher conduit connect- 120 ing with the conveyer for receiving the pusher after transit, and means for stop- ping the pusher and transferring it inde- 125 pendently of the load from the conveyer to said conduit.

48. In an apparatus of the class described, a conveyer, a pusher, means for separating the pusher from the load at the receiving terminal and a pusher conduit connect- 130 ing with the conveyer for receiving the pusher after transit closed at its delivery end and 135

said conduit being of such size as to permit the air to escape past the pusher.

49. In an apparatus of the class described, a conveyer, a pusher, a pusher return conduit independent of the conveyer, and means for transferring the pusher from the conveyer to the return conduit independently of the load.

50. In an apparatus of the class described, a conveyer, a pusher, a pusher return conduit, and a valve normally closing the pusher return conduit and closing the conveyer when moved to open the return conduit.

51. In an apparatus of the class described, a conveyer, a pusher, means for stopping the pusher and holding it in position to close the conveyer, a pusher return conduit, means for opening and closing the delivery end of the conveyer, and means for transferring the pusher from the conveyer to the return conduit controlled by the opening and closing of the delivery end of the conveyer.

52. In an apparatus of the class described, a conveyer, a pusher return conduit, a pusher, a pusher transerrer delivering the pusher to the return conduit, means for opening and closing the receiving terminal of the conveyer, and a yielding connection for operating said transerrer by the opening and closing of the receiving terminal.

53. In an apparatus of the class described, a conveyer, a pusher, a pusher return conduit, a pusher transerrer for delivering the pusher from the conveyer to the return conduit, locking devices for locking said transerrer in normal position, and means controlled by the pusher for unlocking said transerrer.

54. In an apparatus of the class described, a vertical ammunition receiver mounted to swing vertically for removal of the ammunition and having locking devices at the side of the receiver acting to lock the receiver in its ammunition removing position and released by the removal of the ammunition.

55. In an apparatus of the class described, a receiving terminal having in combination a yieldingly supported projectile abutment, and means for automatically locking said abutment against recoil.

56. In an apparatus of the class described, a receiving terminal having in combination a yieldingly supported projectile abutment, and a friction clutch for automatically locking said abutment against recoil.

57. In an apparatus of the class described, a receiving terminal having in combination a projectile abutment, an air cushion for said abutment, and a friction clutch for automatically locking said abutment against recoil.

58. In an apparatus of the class described, a receiving terminal having in combination

a projectile abutment, an air cushion for said abutment, a clutch for automatically locking said abutment against recoil, and means for unlocking said clutch by the movement of parts of the receiving terminal.

59. In an apparatus of the class described, the combination with a main air valve and an auxiliary valve controlling the opening of the main valve, of pneumatic devices for controlling from the receiving terminal the operation of both said valves.

60. In an apparatus of the class described, the combination with a main air valve and an auxiliary valve controlling the opening of the main valve, of devices operated pneumatically from the receiving terminal to control the closing of the main valve independently of the auxiliary valve and to lock and unlock the auxiliary valve to prevent and permit the opening of the main valve.

61. In an apparatus of the class described, the combination with a main air valve and an auxiliary valve controlling the opening of the main valve, of an air pipe for pressure fluid extending to the receiving terminal and from the receiving terminal to the despatching terminal, and devices operated by the release of pressure in said air pipe at the receiving terminal to secure the closing of the main valve and lock the auxiliary valve against operation to open the main valve and operated by the transmission of pressure from the receiving terminal to the despatching terminal to unlock said auxiliary valve.

62. In an apparatus of the class described, a despatching terminal, a receiving terminal, an air supply, an air valve controlling the admission of air for transmission, a gate closing the despatching terminal, an air pipe extending from the air supply to the receiving terminal and from the receiving terminal to the despatching terminal, valve devices at the receiving terminal for controlling the transmission of pressure through said air pipe, and devices operated by the release of pressure in said air pipe at the receiving terminal to permit the opening of said gate and prevent the opening of the air valve and operated by the transmission of pressure through said air pipe from the receiving terminal to the despatching terminal to permit the opening of the air valve for transmission.

63. In an apparatus of the class described, the combination with a gate closing the despatching terminal, of a latch for locking said gate closed, means for releasing said latch, and a catch holding the latch out of locking position and tripped by the movement of the gate to permit the latch to return to locking position.

64. The pneumatic loading conveyer having pusher stops projecting into the con-

veyer and arranged to stop the pusher behind the shell while permitting the shell to pass the stops without injury to said shell.

65. The pneumatic conveyer having pusher stops 174 projecting into the conveyer and arranged to stop the pusher behind the shell while permitting the shell to pass the stops, and yielding pusher catch 175.

66. The combination with the conveyer having pusher stops projecting into the conveyer and arranged to stop the pusher behind the shell while permitting the shell to pass the stops uninjured, of a pusher having buffer ring 223 for engaging said stops.

15 67. The combination with the conveyer having stops 174 projecting into the conveyer and arranged to stop the pusher behind the shell while permitting the shell to pass the stops, and yielding catch 175, of a 20 pusher having buffer ring 223 for engaging said stops, and a shoulder engaged by said catch.

68. The combination with valve 20 having fixed stops 174 and catch 175, of a pusher 25 adapted to engage said stops and be held against rearward movement by the catch, and valve catch 176 tripped by the receipt of the pusher to permit the movement of the valve.

30 69. The combination with valve 20 having fixed stops 174 and catch 175, of a pusher adapted to engage said stops and be held against rearward movement by the catch, 35 valve catch 176 tripped by the receipt of the pusher to permit the movement of the valve, and catch 176^a co-acting with stop 178^a to prevent the return of the valve until the pusher has been delivered.

70. The combination with valve 20 having 40 fixed stops 174 and catch 175, of a pusher adapted to engage said stops and be held against rearward movement by the catch, valve catch 176 tripped by the receipt of the pusher to permit the movement of the valve, 45 catch 176^a co-acting with stop 178^a to prevent the return of the valve until the pusher has been delivered, and cam 180 for withdrawing said catch 175 to permit the rearward movement of the pusher.

Copies of this patent may be obtained for five cents each, by addressing the "Commissioner of Patents, Washington, D. C."

71. A pusher for pneumatic conveyers having a buffer ring 223 at its forward end and a flexible piston ring at its rear end with lugs 231 behind the piston ring for supporting the rear end of the pusher. 50

72. A pusher for pneumatic conveyers having a flexible piston ring at its rear end with lugs 231 behind the piston ring for supporting the rear end of the pusher. 55

73. A hollow pusher for pneumatic conveyers adapted to receive the end of the article 60 to be transmitted and having at its forward end a narrow inner side bearing for the article and a space behind the bearing of larger diameter than the space within the bearing whereby the article may rock on the 65 bearing during transmission.

74. A hollow pusher for pneumatic ammunition conveyers adapted to receive the small end of a cartridge and provided with narrow inner side bearing 226 at its forward 70 end and a space behind the bearing of larger diameter than the space within the bearing. 70

75. A hollow pusher for pneumatic ammunition conveyers adapted to receive the small end of a cartridge and provided with narrow inner side bearing 226 at its forward 75 end and a space behind the bearing of larger diameter than the space within the bearing, and a flexible piston ring.

76. In pneumatic despatch apparatus, a 80 pneumatic transmission tube, a load carrying device to travel through said tube by pneumatic pressure, means for establishing a flow of air through said tube for driving said device through said tube, and means to 85 automatically unload said device and direct the load therefrom through a determined path, when said load carrying device arrives at a determined point in its path of travel.

In testimony whereof, I have signed my 90 name to this specification in the presence of two subscribing witnesses, this sixth day of October, A. D. 1909.

JAMES T. COWLEY.
